SOLENOID SWITCH OPERATING MECHANISM
 Steven W. Soos, Brecksville, Ohio, assignor to Westinghouse Electric Corporation, East Pittsburgh, Pa., a corporation of Pennsylvania

Filed Oct. 22, 1959, Ser. No. 843,148
 13 Claims. (Cl. 200—98)

This invention relates to switch operating mechanisms and has particular relation to mechanisms for operating switches such as circuit breakers between two operating positions.

According to the present invention a mechanism of improved construction is provided for operating a switch between a pair of spaced operating positions. The mechanism includes an operating member which is operatively connected to an actuating element of a switch with the operating member mounted for movement between two positions to displace the actuating element between its operating positions. The present invention is particularly applicable to the operation of circuit breakers which are designed to have high current interrupting capacities. In such installations substantial forces must be applied to the circuit breaker actuating elements in order to effect operation of the circuit breakers.

In a further aspect of the invention the operating member is yieldably connected to the actuating element in order to permit movement of the operating member relative to the actuating element when the actuating element is moved to one of its operating positions. Such arrangement minimizes the possibility of damage to the actuating element.

According to a preferred embodiment of the invention the operating member is in the form of a lever having a pair of spaced ends with one of the ends carrying a yieldable means which is adapted for engagement with the actuating element of the circuit breaker. The yieldable means is arranged to carry the actuating element between its operating positions in response to movement of the operating member or lever between its two positions. The operating member is preferably pivotally mounted between its ends for movement about an axis.

To move the operating member in the preferred embodiment a pair of selectively energizable solenoids are preferably provided having displaceable plungers which are operatively connected to the lever at its other end. When one or the other of the solenoids is energized the operating member will be pivoted about its mounting axis to effect displacement of the switch actuating element. A spring is operatively connected to the operating member and to a bracket or lever which is connected to the plungers so that the lever is snapped into its operating positions after passing through an intermediate unstable, neutral position in its path of travel.

The invention further provides that the energized one of the solenoids is automatically de-energized in response to movement of the operating member toward one of its operating positions. For this purpose a solenoid control switch is provided which has a displaceable member which is displaceable to de-energize the solenoids in response to movement of the operating member toward its operating positions subsequent to passage of the operating member through its unstable neutral position.

According to a further aspect of the invention, the circuit breaker and the associated breaker operating mechanism are employed in connection with an electrical motor to start and stop the motor. The arrangement is such that the breaker and its operating mechanism replace the conventional motor contactor.

It is therefore an object of the present invention to pro-

2

vide a mechanism of improved construction for operating a switch.

It is another object of the invention to provide a mechanism of improved construction for operating a circuit breaker having a high current interrupting capacity.

It is a further object of the invention to provide a mechanism for operating a switch including an operating member which carries yieldable means to be connected to an actuating element of the switch for displacing the actuating element in response to movement of the operating member.

It is still another object of the invention to provide an operating mechanism for operating a switch including an operating member having one end yieldably connected to an actuating element of the switch and another end operatively connected to plungers of a pair of solenoids which are energizable to effect movement of the operating member about an axis between its ends.

It is still another object of the invention to provide a switch operating mechanism of the character described which has a minimum number of parts, is of inexpensive construction and which is positive in operation.

It is a still further object of the invention to employ a circuit breaker and an operating mechanism of the character described in combination with an electrical motor to start and stop the motor without the utilization of a conventional motor contactor.

Other objects of the invention will become apparent from the following description taken in conjunction with the accompanying drawings in which

FIG. 1 is a view in front elevation of an operating mechanism constructed in accordance with the teachings of the present invention;

FIG. 2 is a view in side elevation of the mechanism of FIG. 1;

FIG. 3 is a diagrammatic representation of an electrical circuit employed in connection with the mechanism of FIG. 1; and

FIG. 4 is a view in section taken along the line 4—4 of FIG. 1 with parts removed.

The present invention is susceptible of various modifications and uses but is particularly useful as a start-and-stop motor control.

In the preferred embodiment of the invention, a mechanism is provided for operating a unitary circuit interrupter that may be a conventional circuit breaker or switch having a casing enclosing the contacts of the breaker and the operating mechanism therefor and an actuating element, or handle, which extends outwardly of the casing and is adapted for actuation manually.

In accordance with the present invention, a mechanism is provided for throwing the handle or actuating element of the breaker and is constructed so that the space required by the actuating element for the breaker is no greater than the space occupied by the breaker itself with the exception of the operating member which is positioned outwardly of the side of the breaker so as to engage the element. In other words, the mechanism for operating the element of the conventional breaker or switch does not occupy a space which is any longer or wider than the space occupied by the conventional breaker and only extends outwardly of the conventional breaker or switch a distance sufficient to accommodate the member for operating the breaker. This facilitates the assembly of the breaker operating mechanism into conventional panel or switchboards and the application of the breaker to existing installations.

Referring now to the drawings, there is illustrated in FIG. 1 a switch operating mechanism constructed in accordance with the teachings of the present invention. The mechanism may be mounted on a suitable base 1 in association with a switch or circuit breaker 2, also secured

to the base 1, spaced horizontally from the operating mechanism. The operating mechanism is particularly advantageous when employed to operate a circuit breaker having a high current interrupting capacity.

The breaker 2 is a conventional breaker and includes a plurality of input terminals 3 adapted to be connected to a suitable source of electrical voltage (not shown). A plurality of output terminals 4 are also associated with the breaker 2 to be connected to a suitable load device which in the present invention is electrical motor M. In order to transfer the breaker 2 between open and closed conditions there is provided a suitable actuating element 5 extending exteriorly of the breaker housing and which is connected to the breaker mechanism to be displaceable in vertical directions between two limit or operating positions wherein the breaker is respectively in open and closed conditions.

In order to effect displacement of the element 5, which is conventionally a manually thrown element, the present invention provides an operating mechanism which includes an operating member illustrated in the form of a lever 6 having a first portion 7 which is of generally flat planar configuration connected to a central portion 8 which extends substantially transverse to the part 7 and which has secured to its lower end, as viewed in FIG. 2, a flat portion 9 which lies in a plane spaced from and parallel to the plane of the part 7. The operating member or lever 6 may be formed of any suitable material and is preferably constructed of a metallic material having substantial rigidity.

In order to permit connection of the operating member 6 to the actuating element 5 the left hand part 7 of the operating member is provided with an opening 10 which registers with the element 5. In accordance with one feature of the present invention the operating member 6 is yieldably connected to the actuating element 5. To this end the invention provides yieldable means which is carried by the part 7 of the operating member and which is arranged to engage the element 5. As best shown in FIG. 1, the yieldable means includes wire means preferably consisting of a pair of wire forms 11 of identical configuration. Each of the wire forms includes a central wire section 11a and a pair of terminal sections 11b. The yieldable connection is provided by associating a pair of the forms 11 in reversed relationship such that the central sections 11a extend along substantially parallel spaced axes. The terminal sections 11b are connected to a pair of studs 11' which may be secured to the portion 7 of the operating member 6 in any suitable manner. It is noted with reference to FIG. 1 that the spaced central sections 11a define a passage 12 which is proportioned to receive the actuating element 5. The opening 10 of the portion 7 is configured to have a dimension in the direction of spacing of the sections 11a which is somewhat greater than such spacing, so that the element 5 may project through the opening 10 without preventing engagement of the element 5 with the central sections 11a.

In order to mount the operating member or lever 6 for movement to carry the element 5 between its operating positions the operating member is pivotally mounted for movement through a plane which is parallel to the direction of spacing of the operating positions of the element 5. To this end the operating member 6 is pivotally mounted between its ends by a suitable pin 14, which is secured to the part 7 of the operating member and which extends through an opening of a projection 15 formed on a side 16 of a bracket 17 which has a flat base portion 18 which is secured to the base 1 in any suitable manner. Washers 19 are positioned to surround the pin 14 and a cotter pin 20 may be provided to extend through an opening of the pin 14 to maintain the washers in position.

The operating member 6 is operatively connected to a pair of solenoid devices described hereinafter by means comprising a bracket or lever 21 of generally U-shaped

configuration having a base portion 22 and a pair of spaced legs 23 projecting from the base portion in spaced parallel relation. The bracket or lever 21 is mounted to a suitable support 24 which is of U-shaped configuration having a base 25 which is secured to a side 26 of the bracket 17 and which has a pair of spaced legs 27 extending from the base 25. A suitable pivot pin 28 extends through the pair of legs 27 and the pair of legs 23 to mount the lever 21 for pivotal movement about the axis of the pin 28.

The operating member 6 is actuatable with a snap-action between two operating positions by a suitable spring construction associated with the lever 21 and the operating member 6. For this purpose the base 22 of the lever 21 includes a restricted portion 29 to which is connected a terminal 30 of a helical spring 31 having its other terminal 32 extending through an opening 33 in the portion 9 of the operating member 6. The operating member 6 is provided additionally with a pair of communicating slots 34 and 34' located respectively in the parts 8 and 9 of the operating member. It is noted that the spring 31 and also one of the legs 23 of the lever 21 extend through the slot 34 and that the spring 31 is positioned within the slot 34'. As will presently appear, the described arrangement is effective to cause a very rapid and positive movement of the lever to its operating positions.

As best shown in FIG. 2, the operating member 6 is supported in part by a suitable roller 36 on the pivot pin 28 adjacent the lower one of the legs 23 of the lever 21. The portion 9 of the operating member 6 rests on the upper surface of the roller 36 and is movable thereover when the operating member is pivoted about the axis of the pin 14.

In order to effect movement of the operating member 6, the present invention provides a pair of electrically energizable solenoids 37 and 38 provided respectively with electroconductive windings 39 and 39'. The solenoids 37 and 38 may be of any suitable construction and are provided respectively with plungers 40 and 41 which are displaceable along parallel axes in response to energization of the solenoids. The plungers 40 and 41 are secured to each other in any suitable manner for movement as a unit and are operatively connected to the lever 21 by a pin 42 carried by the lower one of the legs 23 to extend downwardly between the plungers as shown in FIG. 4. When the plungers are displaced one or the other will engage the pin 42 and movement of the plungers will effect movement of the lever 21 about the axis of the pin 28 to effect movement of the terminal 30 of the spring 31 to cause a snapping movement of the operating member 6 about the axis of the pin 14.

The solenoids may be energized in any suitable manner such as by the operation of a suitable switch 42 shown diagrammatically in FIG. 3. In the present invention a suitable control switch 43 is arranged for operation in response to movement of the operating member 6 to effect de-energization of the energized one of the solenoids 37 or 38. The switch 43 is arranged to be operated subsequent to passage of the spring 31 through the longitudinal axis of the operating member 6 at which time the operating member is snapped to its operating position by action of the spring 31 independently of energization of one of the solenoids. For this purpose the switch 43 is mounted by a vertically extending section 45 of a bracket 46 having spaced legs 47 which may be secured to the side 26 of the bracket 17. The switch 43 includes a displaceable switch member 44 which is mounted in the path of movement of heads of a pair of screws 48 and 49 secured respectively to extensions 50 and 51 of a pair of tabs 52 and 53 which are secured to the part 8 of the lever. It is observed that the member 44 will be displaced between two operating positions by engagement of the member 44 with the heads of the screws 48 and 49 as the lever is moved towards its operating positions.

In FIG. 1, the operating member 6 is shown in one of its operating positions wherein the element 5 is in a position to effect either the opening or closing of the circuit breaker 2. If it is desired to displace the element 5 from the position shown to operate the circuit breaker, the solenoid 37 is energized to accomplish this. The switch 42 is actuated to the left as viewed in FIG. 3 to effect energization of the winding 39 of the solenoid 37 through the closed switch 43 from a suitable source of voltage represented by conductors L1 and L2.

When the solenoid 37 is energized its plunger 40 will be displaced downwardly, as viewed in FIG. 1, to move the pin 42 and the plunger 40 also in a downward direction, with the result that the lever 21 will be pivoted about the pin 28 in a counterclockwise direction, as viewed in FIG. 1. As the spring 31 assumes a position wherein it has just crossed the axis of the length dimension of the operating member 6, the portion 7 of the operating member will be quickly snapped in a clockwise direction and the element 5 will be moved upwardly by the wire forms 11 secured to the portion 7. At this time also the switch 43 is actuated by the lever to the right as viewed in FIG. 3 to effect de-energization of the solenoid 37.

The wire forms provide a yieldable connection which is effective to first cause movement of the element 5 and then to permit movement of the portion 7 of the operating member relative to the element 5 when the element 5 arrives in a limit position. This action minimizes the possibility of damage to the element 5 as it is moved into engagement with its spaced stop means 54 which are ordinarily in the form of edges of a part of the frame of the circuit breaker 2.

As stated hereinbefore, the circuit breaker and its operating mechanism have particular advantages when used in combination with a motor to start and stop the latter. In FIG. 1, the circuit breaker 2 is shown as connected to control a three-phase motor M and the solenoids 37, 38 are energizable to open and close the breaker 2 to start and stop the motor. When the described breaker and operating mechanism are used in combination with the motor, it is not necessary to employ the conventional motor contactor. A motor contactor is an expensive item and, in addition to the contactor, a circuit breaker must be provided because of the limited current interrupting capacity of contactors. Conventionally, a contactor is rated to interrupt currents of magnitudes approximately 8 to 10 times greater than the normal load current to the motor. A circuit breaker, on the other hand, is designed to have an interrupting capacity of between 800 and 1,000 times normal load current. The current interrupting capacity of a breaker is then approximately 100 times greater than that of a contactor.

The present invention provides a circuit breaker which may be used to start and stop a motor in place of a motor contactor. The arrangement is such that if the circuit breaker fails, a conventional circuit breaker may be purchased to replace the one that failed and the cost of replacing such a breaker is nominal. In fact, the breakers can be replaced several times without approaching the initial cost of a motor contactor. The described breaker and operating mechanism provides the advantages of remote control and is, therefore, ideally suited for use in place of a motor contactor to start and stop a motor.

Although the invention has been described with reference to certain specific embodiments thereof, numerous modifications are possible and it is desired to cover all modifications falling within the spirit and scope of the appended claims.

Having thus described my invention, I claim:

1. In combination, a unitary circuit interrupter comprising a casing, an operating handle extending from said casing and movable between two operating positions to operate said circuit interrupter to open and close an elec-

tric circuit, a mechanism for operating said circuit interrupter comprising an operating member, means effecting a yieldable connection between said operating member and said operating handle, and means comprising a pair of solenoids and armature means operatively connected to said operating member and operable to move said operating member to thereby move said operating handle to open and close said electric circuit.

2. In combination, a unitary circuit interrupter comprising a casing, an operating handle extending from said casing and movable between two operating positions to operate said circuit interrupter to open and close an electric circuit, a mechanism for operating said circuit interrupter comprising an operating member, means effecting a yieldable connection between said operating member and said operating handle, electric operating means comprising a pair of solenoid coils and armature means, and said armature means being movable in opposite directions upon alternate energization of said solenoid coils to move said operating member to thereby move said operating handle between said two operating positions.

3. In combination, a unitary circuit interrupter comprising a casing, an operating handle extending from said casing and movable between two operating positions to operate said circuit interrupter to open and close an electric circuit, stop means positioned to engage said operating handle to limit movement of said operating handle at each of said two positions, a mechanism for operating said circuit interrupter comprising an operating member, means effecting a yieldable connection between said operating member and said operating handle, means comprising a pair of solenoids and armature means operatively connected to said operating member and operable to move said operating member to thereby move said operating handle to open and close said electric circuit, and said yieldable connection yielding to permit limited movement of said operating member relative to said operating handle when said operating handle engages said stop means.

4. In a mechanism for operating a circuit interrupter, said circuit interrupter having an actuating element movable between a pair of spaced operating positions, an operating member having spaced end portions with one of the end portions operatively connected to said element, means mounting said member for movement through a plane about an axis between said end portions transverse to said plane and transverse to the direction of spacing of said operating positions, a lever having a pair of spaced end sections, means mounting the lever at one of the end sections for movement about a second axis spaced from and parallel to the first axis, a pair of selectively energizable solenoids each having a plunger with the plungers operatively connected to said lever, said lever being movable about the second axis in response to movement of said plungers, and resilient means having a pair of terminals secured respectively to the other of said end portions and to the other of said end sections.

5. A mechanism as defined in claim 4 wherein said first and second axes are included in a plane which passes through the approximate center of the path of movement of said actuating element, said first axis being located between said second axis and said approximate center.

6. A mechanism as defined in claim 4 in combination with control switch means operable to de-energize said solenoids, said control switch means having a displaceable member effective when displaced in each of two directions for de-energizing a separate one of said solenoids, said displaceable member being displaced in response to predetermined movement of said operating member to de-energize the solenoid which effects such movement of the operating member.

7. A mechanism as defined in claim 4 wherein said one of said end portions is yieldably connected to said actuating element.

8. In combination, a unitary circuit interrupter comprising a casing, an actuating element extending from said casing and operable to operate said circuit-interrupter to open and close an electric circuit, an operating member operable to operate said actuating element, a lever, an overcenter spring attached at one end to said lever and at the other end to said operating member, said overcenter spring being movable upon operation of said lever to thereby operate said operating member, electric operating means comprising a pair of solenoid coils, and armature means movable in opposite directions upon alternate energization of said solenoid coils to effect operation of said lever.

9. A mechanism for operating a circuit interrupter, said circuit interrupter having an actuating element operable to effect opening and closing of said interrupter, an operating member operable to operate said actuating element, a lever, an overcenter spring connecting said operating member to said lever, said overcenter spring effecting operation of said operating member upon operation of said lever to thereby effect opening and closing of said circuit interrupter, electric operating means including a pair of solenoid coils and armature means movable in opposite directions upon alternate energization of the solenoid coils, and switch means automatically operable during opening and closing operations to effect deenergization of the energized solenoid coil.

10. In combination, a unitary circuit breaker comprising a casing, an actuating element extending from said casing and being movable between spaced operating positions to operate said circuit breaker to open and close an electric circuit, said circuit breaker being constructed to interrupt more than five hundred times its normal load current, an operating member operatively connected to said actuating element, means mounting said operating member for movement through a plane about an axis extending normal to said plane and normal to the direction of spacing of said operating positions, overcenter spring means movable between two overcenter positions to operate said operating member to alternately open and close said circuit breaker, solenoid operating means successively energized to alternate said overcenter spring means between said two positions, and switch means automatically operable upon the occurrence of each energized operation of said solenoid operating means to deenergize the solenoid operating means.

11. In combination, a unitary circuit breaker having an interrupting capacity of at least five hundred times its normal load current, said circuit breaker comprising a casing, an actuating element extending from said casing and movable between spaced operating positions to operate said circuit breaker to open and close an electric circuit, an operating member having spaced end portions with one of said end portions operatively connected to said actuating element, means mounting said operating member for movement through a plane and about an axis disposed between said end portions, said axis being disposed generally perpendicular to said plane and generally perpendicular to the direction of spacing of said operating positions, overcenter spring means operatively connected to the other of said end portions of said operating member and movable back-and-forth between two overcenter positions to alternately open and close said circuit breaker, solenoid operating means comprising a pair of solenoids, armature means operatively connected to said overcenter spring means, said armature means being movable in opposite directions upon alternate energization of said solenoids to alternate said overcenter spring means

between said two positions, and switch means automatically operable during opening and closing operations to effect deenergization of the energized solenoid.

12. In combination, a unitary circuit breaker having an interrupting capacity of at least five hundred times its normal load current, said circuit breaker comprising a casing, an actuating element extending from said casing and operable to operate said circuit breaker to open and close an electric circuit, an operating member operable to operate said actuating element, electric operating means operable to operate said operating member, said electric operating means comprising overcenter spring means operatively connected to said operating member and movable back-and-forth between two overcenter positions to alternately open and close said circuit breaker, solenoid means connected to said overcenter spring means and successively energized to alternate said overcenter spring means between said two positions, switch means automatically operated during each energized operation of said solenoid means to deenergize said solenoid means, and said electric operating means being mounted at the side of said circuit breaker and having a length not substantially greater than the length of said circuit breaker and having a depth not substantially greater than the depth of said circuit breaker.

13. In combination, a unitary circuit breaker comprising a casing, an actuating element extending from said casing and operable to operate said circuit breaker to open and close an electric circuit, said circuit breaker being constructed to interrupt at least five hundred times its normal load current, an operating member operable to operate said actuating element, electric operating means operable to operate said operating member and comprising overcenter spring means movable back-and-forth between two overcenter positions to alternately open and close said circuit breaker, solenoid means successively energized to alternate said overcenter spring means between said two overcenter positions, switch means automatically operated during each energized operation of said solenoid means to deenergize said solenoid means, said electric operating means being mounted at the side of said circuit interrupter, and said electric operating means having a length not substantially greater than the length of said circuit breaker and having a width not substantially greater than the width of said circuit breaker and having a depth not substantially greater than the depth of said circuit breaker.
